UNITED STATES PATENT OFFICE

2,665,438

BEATING DEVICE FOR CLEANING
DUST MOPS

Bert T. Insley, San Francisco, Calif., assignor, by
mesne assignments, to The Edwin Corporation,
a corporation of California.

Application May 15, 1950, Serial No. 161,963

12 Claims. (Cl. 15—91)

1

This invention relates to a dust mop cleaner and has for one of its objects the provision of a device for cleaning a dust mop more efficiently than heretofore and without injury to the mop.

Another object of the invention is a sanitary dust mop cleaner that is adapted to be foot operated and which cleaner is adapted to function as a holder for supporting the mop with the yarn or cords of the mop head suspended when the mop is not in use, and which cleaner is relatively small and easily and inconspicuously stored on the floor in a corner of a closet or room.

A still further object of the invention is a dust mop cleaner that is provided with a beater that is foot actuated for rapidly beating the mop head in the most efficient manner for removing the dust therefrom, and which beater moves in a generally oscillatory manner.

Heretofore dust mop cleaners have been provided which, in most instances have a rotary movement that tends to impart a rotary movement to the yarn or cords that go to make up the mop head. The mop is not beaten, and the result is that much of the dust remains in the mop head.

Also, heretofore, the cleaners for dust mops have been relatively large, which is a serious objection, particularly where storage space is at a premium and the housekeeper is critical as to appearances. A large, bulky device merely for cleaning the dust from a mop head is undesirable.

With the present invention, the cleaner is relatively small and is adapted to beat the mop head with sharp, strong blows from opposite sides and in a direction from the base or held ends of the cords generally toward their free outer ends whereby dust clinging to the cords will be certain to be knocked off. Also, with the present invention, the mop and cleaner are cooperatively formed for quick insertion of the mop head into the cleaner and within the same when the handle is swung to a vertical position and which mop may be quickly removed from the cleaner when desired by swinging the handle to a slightly inclined position and moving the mop laterally.

Other objects and advantages will appear in the drawings and in the description.

2

In the drawings,

Fig. 1 is a top plan view of the cleaner with the mop head therein.

Fig. 2 is a side view of the cleaner shown in Fig. 1.

Fig. 3 is an end view of the cleaner of Fig. 1.

Fig. 4 is a fragmentary sectional view of the end of the cleaner through which the mop head is inserted into the cleaner with the door over the entrance opening being open.

Fig. 5 is an enlarged sectional view taken vertically through the cleaner with the mop head indicated in section and with the several positions of the beater indicated.

Fig. 6 is an enlarged fragmentary horizontal sectional view taken through lines 6—6 of Fig. 5 showing the cleaner from above the level of the beater.

Fig. 7 is a sectional view taken along line VII—VII of Fig. 5.

Fig. 8 is a sectional view taken along line VIII—VIII of Fig. 6.

Fig. 9 is a perspective view of the mop head.

Fig. 10 is an enlarged fragmentary sectional view showing the structure for locking the mop head to the cleaner.

Fig. 11 is a sectional view similar to that of Fig. 10 with the mop handle vertical and locking the head of the mop to the cleaner, and Fig. 12 is a fragmentary view of the handle lock.

In detail, the device shown in the drawings comprises a housing, generally designated 1, having a pair of opposed end walls 2, 3 (Fig. 2) opposed side walls 4, 5 (Figs. 3, 5) a bottom wall 6 and a top wall 7.

The top wall 7 is formed with a central depression or channel 8 that extends longitudinally thereof from the edge adjacent end wall 3, and which channel terminates at about the center of the top wall. An upstanding rib 9 is formed in the bottom of channel 8 and longitudinally thereof, which rib is centrally between the sides of said channel and becomes progressively higher in direction away from the end wall 3. The inner end of said rib terminates in a depression 10 (Figs. 10, 11) that extends transversely thereacross adjacent to the inner closed end of channel 8.

The upper portion of end wall 3 comprises a door 12 (Fig. 3) that is hinged along its lower

edge at 13 for swinging of its upper end downwardly. The hinge includes a horizontal hinge pin about which is a torsion spring 14 at a point intermediate its ends so connected with the door and end wall as yieldably to urge the door to a closed position at all times.

Provision for opening the door is by foot operated member 15 that projects outwardly from the wall 3. An upward extension 16 (Fig. 4) of said member extends through end wall 3 and upwardly, the upper end having a neck 17 that projects into a recess 18 formed in the inner side of door 12. The end of said neck 17 may be pivotally secured to said door in said recess as indicated, so that upon pressing downwardly on the projecting member 15 by the foot, the door will be swung downwardly and outwardly to the position seen in Fig. 4 whereby the head of a mop, hereinafter described, may be inserted into said housing.

The mop best adapted for use with the present cleaner, may be of the type in which the yarn, string, or cords 19 are secured to a fabric sheet 20 and are adapted to depend from said sheet when the latter is horizontal. An upper sheet 21 is adapted to be secured along its edges to the edges of the sheet 20, except at one end where a gap between edges 22 is provided to enable the spring wire frame on the mop stick 23 to enter the space between sheets 20, 21.

This frame comprises a wire 24 that is generally of U-shape to follow the contour of the edges of sheets 20, 21 and the ends of the legs of said U extend inwardly toward each other as at 25 (Fig. 9) for a short distance, and then outwardly of the sheets at the edges 22 of sheet 21 to return bends 26. From bends 26 the lengths 27 of wire extend over the upper sheet 21 and generally convergently to points about over the center of said sheet where their ends are connected by a straight length 28 that pivotally extends through a horizontal sleeve 29 eccentrically secured to the lower end of mop stick 23 in any suitable manner.

A strip 30 may connect the lengths 27 adjacent sleeve 29.

Sleeve 29 is centrally cut away along one side as at 32 (Fig. 9) and this cut away portion is adapted to slidably pass the upstanding rib 9 upon sliding the mop head into the housing through the opening in end wall 3 with the lengths of wire 27 and the handle above top wall 7. However, when the mop head is fully within the housing, the sleeve is then over the transverse depression 10 and by swinging the handle 23 upwardly to vertical the side of sleeve 29 adjacent the cut away section 32 will rotate into the depression locking the mop head against removal from the housing until the handle is again swung downwardly a sufficient distance to enable the cut away portion to fit over the rib 9.

The fact that the sleeve 29 is eccentric to the handle enables the handle to stand vertically on its lower end when it is swung to vertical position, as best seen in Fig. 2. The handle may swing slightly past vertical to insure its weight holding it upright on the top wall 7.

It is pertinent to note that the handle need not be swung to horizontal in order to remove the mop. Only a relatively slight inclination of say 20 degrees relative to vertical, or even less is sufficient.

Within the upper end of the housing 1 is a mop head guide comprising a horizontally disposed U-shaped wire or rod 33. The free end 75

portions 34 (Fig. 1) defining the sides of the U are inclined upwardly at about an angle of 45° and then extend oppositely outwardly to the sides of the housing to which the terminating ends are secured. The closed end of the U is secured to end wall 2 and the sides are spaced inwardly to generally follow the contour of the mop head. Upon insertion of the mop head into the housing, the flattened yarn or string will be engaged by the inclined ends of the guide, which will draw the same downwardly into the path of travel of the beater. The wire frame of the mop head will remain above the guide and adjacent the top of the housing. The closed end of the U is indicated at 35.

The foregoing explanation has been concerned with the step of getting the mop head into the housing. It may be quickly recovered by swinging the handle generally to the side in direction toward door 12 and then merely moving the mop out of the door. The door will automatically open under the force required to remove the mop head, although the operator may actuate the foot engaging member 15 if so desired.

The top wall 7 is preferably formed with small recesses 36 (Fig. 1) along the edge adjacent the door 12 to receive the return bends 26 of the wire 24. When the return bends are in said recesses 36, the door may be fully closed and is reasonably dusttight. The said door is provided with an inwardly projecting horizontally disposed rib 37 that is adjusted to force the depending strands on the mop into the path of the beater, as will later be explained.

In order to replace the fabric and strings of the mop head, it is merely necessary to force the return bends 26 toward each other until the wire frame 24 can be pulled out of its position between sheets 20, 21 through the gap in sheet 20 between the said edges 22.

Centrally positioned between the ends of the housing, and on the bottom, is a horizontally elongated box 40 extending at right angles to the horizontal longitudinal axis of the housing. This box 40 may comprise a flat base strip 41 secured to the bottom 6 of the housing and over which is an inverted channel strip having sides 42, 43 and a bottom 44, the latter forming the top of the box. The sides of this channel strip are secured along their free lower edges to the flat base strip 41.

The said sides 42, 43 are cut away as at 44' (Figs. 5, 8), providing horizontally extending openings in said sides through which a cross bar 45 is adapted to extend with the opposite end portions of said bar projecting outwardly of opposite sides of said channel.

Adjacent and preferably in sliding contact with the opposite outer sides of said channel strip are seal plates 46 (Figs. 8, 9) through which the projecting ends of the cross bar 45 extend in a close fit. These plates have flanges 47 that extend toward each other over the upper sides of the top of box 40, and the length of said plates is sufficient to cover said recesses 44 when the cross bar 45 is reciprocably moved in direction transversely thereof between opposite ends of said recesses.

A pair of rollers 48 are on bar 45 adjacent the inner sides of the side walls 42, 43 of the box 40. These roll on the base plate 41 when the bar is reciprocated.

A coil or helical spring 49 is within box 40 and is secured at one end to the bar 45 centrally between the ends of the latter, while the other end

of said spring is secured to an end wall 50 (Fig. 5) that closes one end of the channel strip forming the sides and top of said box 40. This spring tends at all times to hold the bar 45 at the end of the recess 44' nearest end wall 50, and automatically returns bar 45 to said end of the recess when the bar is urged toward the opposite end of said recess and released.

As seen in Fig. 5, the channel strip that forms the sides and top of box 40 extends through the side wall 4 of the housing 1. Extending upwardly from the said channel strip and adjacent the outer side of side wall 4 is a channel strip generally designated 52. The free edges of sides 53 of said strip 52 are against the outer side of side wall 4, and coplanar flanges 54 projecting outwardly from said sides 53 along their free edges are secured to said side wall 4 by any suitable means.

The upper end of the channel strip 52 is provided with a bearing 55 that supports a roller 56 in a position at the upper end of the said strip. This roller is between the adjacent sides of a pair of similar arcuately extending arms 58 constituting a link. A web 59 connects said arms adjacent one of their ends, which web is curved longitudinally to follow the curves of the arms 58, and the roller 56 engages the convexly curved side of the web.

Said arms 58 extend through an opening formed in the side of wall 4 at their ends that are connected by said web, and upwardly alongside the side wall 4 above channel strips 52. The opposite ends of arms 58 extend into the box 40 through openings 60 formed in the upper side 44 of said box (Fig. 8). The terminating ends of the arms 58 within box 40 are secured to the cross bar 45.

From the description up to the present point it will be seen that by pushing downwardly on the ends of arms 58 that are outside the housing 1, the cross bar 45 will be moved in the box 40 longitudinally of the latter and the spring 49 will be tensioned or expanded. The roller 56 will function to support the arms and to guide them through the openings into the housing, and the web 59 will not only function as a track in engagement with roller 56, but it will tend to close the opening through which the arms and web extend into the housing.

Provision for pushing the upper ends of arms 58 downwardly is in the form of a foot pedal 61 that projects outwardly from the wall 4 of the housing. This pedal 61 has an upward extension 62. Extension 62 is in the form of a channel strip having a closed upper end 63 that extends over the upper end of arms 58, and sides 64. The arms 58 extend between sides 64 and are enclosed by said sides and by the wall 65 that connects the sides 64. A pivot 66 is carried by the upper end of the upward extension 62 to which the upper ends of arms 58 are pivoted. Also the pedal 61 and extension 62 may be swung outwardly on pivot 66 to expose the roller 56 and upper ends of arms 58 if desired. An anti-friction block 67 may be carried by the upward extension 62 of pedal 61 for slidable engagement with the outer surface of the bottom of channel strip 52. The said bottom of strip 52 may be longitudinally recessed to guide the block during sliding thereof.

By pressing downwardly on pedal 61 the cross bar 45 is moved in box 40 in direction away from side wall 4 and toward wall 5. Upon release of downward pressure on said pedal, the spring 49 will return the cross bar to its original position.

Arms 58 move longitudinally during the foregoing operation and substantially no gap exists in side wall 4 where dust may escape from the box.

5 Pivotedly secured to the outwardly projecting ends of cross bar 45 are one of the ends of a pair of beater arms 69. These arms 69 extend slantingly upwardly toward side wall 5 when the pedal 61 and the outer ends of arms 58 are in their uppermost positions, and the upper ends of arms 69 remote from the cross bar 45 carry a horizontal beater rod or element 70 that extends through and between said upper ends and equal distances outwardly thereof (Fig. 6). Between the beater element 70 and the cross bar 45 is a cross rod 71 that connects said arms, and a helical or coil spring 72 connects said cross rod with the top of box 40 at a point about midway between the end positions of the cross bar 45 when the latter is reciprocated.

When the pedal 61 is moved downwardly and the cross bar 45 is moved toward wall 5, the beater arms 69 will also be moved toward the wall 5 carrying the beater element therewith, but as the spring 72 becomes tensioned, it will tend to pull the upper ends of arms 69 and the beater element toward wall 4 about the cross rod 45 as a pivot.

Adjacent wall 5 is a bracket member 73 that carries a pair of horizontally spaced bumpers 74. These bumpers are on a horizontal cross piece 75 that is secured to the upper end of the bracket, and the ends of the beater element that project outwardly of arms 69 rest on these bumpers when the pedal 61 is inoperative for causing actuation of the beater element. Said bumpers are preferably of resilient material, such as rubber, and function to take the shock of the element 70 at the one end of its stroke.

Adjacent the wall 4 is a cross piece 76 that is similar to cross piece 75 and that has bumpers 77 thereon (Fig. 6).

These bumpers 74 and 77 are respectively on plates 78, 79 that are integral with the cross pieces 75, 76. Plates 78 have oppositely inwardly projecting lugs 80 thereon and plates 79 have similar oppositely inwardly projecting lugs 81 thereon.

The arms 69 have laterally oppositely outwardly directed flanges 82 along their upper edges, and similar flanges 83 along their lower edges (Figs. 5, 6) when the beater element is resting on bumpers 74.

Upon downward movement of the pedal 61 and consequent longitudinal movement of arms 69, the lower flanges 83 will pass below lugs 80 on plates 78 and the arms cannot be swung to carry the beater element from a position adjacent wall 5 to a position in which the beater element rests on bumpers 77 until the flange passes from below the lugs 80. The result of this is that the outer upper ends of arms 69, and the beater element 70, moves upwardly to a point adjacent the upper ends of the depending mop strings before it is released, and during this upward movement the spring is tensioned so that appreciable power is stored before the arms are released.

The movement of the beater, when the arms are released, is generally downwardly and across the housing to the bumpers 77.

As soon as the foot pedal is released, after the beater has moved from its position adjacent wall 5 to bumpers 77, the spring 49 will not only elevate the pedal but will pull the cross rod back to the full line position shown in Fig. 5 with the

result that flanges 82 will engage lugs 81 to cause the beater element to move upwardly before its release in the same manner as happened when the beater element was adjacent the opposite side of the housing and the pedal was depressed.

It is pertinent to note that the action of the beater element is quite fast when it is released and its movement is generally downwardly, the result being that the dust is thoroughly beaten from the mop. Only a few reciprocal movements of the beater element will clean the mop head. The mop may then be removed for use, or it may be left in the housing with the handle upright, in which position the mop head is concealed and the housing takes up but little more space than the mop head. Thus the cleaner becomes a support and storage device for the mop in addition to its cleaning function.

Inasmuch as the yarn or strings making up the body of the mop head become flattened out when the mop is used, the value of the guide 33 and the rib 37 on the door become apparent. Unless the flattened body of yarn, string or the like is positioned within the path of travel of the beater, the latter would not perform its function. The guide 33 and rib 37 insure the yarn or strings being pressed inwardly and below the guide 33, and the generally laterally and downward swing of the beater efficiently beats the dust from the yarn or string and at the same time tends to straighten out the yarn or string for hanging vertically.

The closed end of the U, if anything, is wider than the width of the end of the mop adjacent thereto, thus facilitating the vertical straightening of the yarn or string at the toe and of the mop head.

It is to be noted that the channel strip forming the sides and top of box 40 projects outwardly of the side of the housing to a point below the pedal 6. This projecting end of said strip engages the floor or any other supporting surface through a pad or foot 51 thereby stabilizing the cleaner during the cleaning operation, so it will not overturn as the pedal is vertically reciprocated.

In Fig. 12, the handle lock is most clearly shown for releasably locking the handle upright on the housing, although, as already stated it will tend to remain upright. The sleeve 29 has its opposite end edges outwardly recessed as indicated at 90 and the length 28 of the wire 27 may be split as at 29 between the ends of the sleeve so that the wire will spring into recesses 90 when the handle is vertical to hold said handle in a vertical position. When the handle is forcibly swung downwardly the wire will spring out of the recesses.

I claim:

1. A dust mop cleaner for a dust mop head having a main body of fibrous material secured to a holder therefor, said cleaner comprising a support for said mop head adapted to hold said holder with said body suspended therefrom, a beater element supported below said support for generally oscillatory movement in a vertical plane across the space adapted to be occupied by said body when said holder is held by said support, a spring connected at one of its ends to said element for so moving the latter upon tensioning of said spring to a predetermined degree and a spring tensioning member connected with the other end of said spring and actuatable by an operator for moving said element for so tensioning said spring.

2. A dust mop cleaner for a dust mop head having a main body of fibrous material secured to a holder therefor, said cleaner comprising a support for said mop head adapted to hold said holder with said body suspended therefrom, a beater element supported below said support for generally oscillatory movement in a vertical plane across the space adapted to be occupied by said body when said holder is held by said support, a spring connected at one of its ends to said element for so moving the latter upon tensioning of said spring to a predetermined degree and a spring tensioning member connected with the other end of said spring and actuatable by an operator for moving said element for so tensioning said spring, a stationary stop for holding said element from said movement until said spring is under a predetermined tension, said element being releasable from said stop upon said spring being tensioned to said predetermined degree.

3. A dust mop cleaner for a dust mop head having a main body of fibrous material secured to a holder therefor, said cleaner comprising a support for said mop head adapted to hold said holder with said body suspended therefrom, a beater element supported below said support for generally oscillatory movement in a vertical plane across the space adapted to be occupied by said body when said holder is held by said support, a spring connected at one of its ends to said element for so moving the latter upon tensioning of said spring to a predetermined degree and a spring tensioning member connected with the other end of said spring and actuatable by an operator for moving said element for so tensioning said spring, said oscillatory movement being generally downwardly from an elevated position at opposite sides of said space and means for supporting said element for such generally downwardly movement.

4. A dust mop cleaner for a dust mop head having a main body of fibrous material secured to a holder therefor, said cleaner comprising a support for said mop head adapted to hold said holder with said body suspended therefrom, a beater element supported for generally oscillatory movement below said support and across the space adapted to be occupied by said body when said holder is held by said support, a spring connected with said element for so moving the latter upon tensioning of said spring to a predetermined degree, and a spring tensioning member connected with said spring and actuatable by an operator for so tensioning said spring, said oscillatory movement being generally downwardly from an elevated position at opposite sides of said space and means for supporting said element for such generally downwardly movement, including a pivot supported for generally reciprocable movement horizontally below the space adapted to be occupied by said body.

5. A dust mop cleaner for a mop head having a main body of fibrous material secured to a holder therefor, comprising; a housing having a top wall, opposed side walls, opposed end walls and a bottom wall, one of said end walls including a door swingable to open position for admitting said body into said housing and said top wall being adapted to carry said holder with said body suspended therefrom when said body is so moved into said housing, a pair of stationary bumpers respectively adjacent each of said side walls, a beater element, an arm extending generally downwardly from said element carrying the latter at its upper end and a pivot supporting the

lower end of said arm for swinging of said element in an oscillatory manner between said bumpers, a spring connected with said arm adapted to be tensioned for swinging said element under the power of said spring upon causing reciprocable movement of said pivot, and means connected with said pivot projecting from said housing for movement by an operator for causing said reciprocable movement of said pivot.

6. A dust mop cleaner for a mop head having a main body of fibrous material secured to a holder therefor, comprising: a housing having a top wall, opposed side walls, opposed end walls and a bottom wall, one of said end walls including a door swingable to open position for admitting said body into said housing and said top wall being adapted to carry said holder with said body suspended therefrom when said body is so moved into said housing, a pair of stationary bumpers respectively adjacent each of said side walls, a beater element, an arm extending generally downwardly from said element carrying the latter at its upper end and a pivot supporting the lower end of said arm for swinging of said element in an oscillatory manner between said bumpers, a spring connected with said arm adapted to be tensioned for swinging said element under the power of said spring upon causing reciprocable movement of said pivot, and means connected with said pivot projecting from said housing for movement by an operator for causing reciprocable movement of said pivot, said means being an arcuately extending link, one of said side walls being formed with an opening for passage of said link therethrough and for reciprocable movement of said link longitudinally thereof through said opening, a foot pedal connected to the end of said arcuately extending link outside said housing for vertical reciprocation to effect said reciprocable movement of said link, and the end of said link opposite said pedal being connected with said pivot.

7. A dust mop cleaner for a mop head having a main body of fibrous material secured to a holder thereof, comprising: a housing having a top wall, opposed side walls, opposed end walls and a bottom wall, one of said end walls including a door swingable to open position for admitting said body into said housing and said top wall being adapted to carry said holder with said body suspended therefrom when said body is so moved into said housing, a pair of stationary bumpers respectively adjacent each of said side walls, a beater element, an arm extending generally downwardly from said element carrying the latter at its upper end and a pivot supporting the lower end of said arm for swinging of said element in an oscillatory manner between said bumpers, a spring connected with said arm adapted to be tensioned for swinging said element under the power of said spring upon causing reciprocable movement of said pivot, and means connected with said pivot projecting from said housing for movement by an operator for causing said reciprocable movement of said pivot, a foot actuatable member connected with said door for swinging the same to open position, a spring connected with said door for automatically closing the latter upon release of said member.

8. A dust mop cleaner for a dust mop head having a main body of fibrous material secured to a holder therefor, said cleaner comprising a housing having a top wall adapted to hold said holder with said fibrous material suspended therefrom within said housing, means respectively

on said top wall and said holder movable relatively into interlocking releasable engagement when said holder is carried by said top wall for holding said holder stationary during beating of said body, a beating element below said top wall supported for generally oscillatory movement back and forth across the space adapted to be occupied by said head when said holder is secured to said top wall, means for so actuating said beater element.

9. A dust mop cleaner for a dust mop head having a main body of fibrous material secured to a holder therefor, said cleaner comprising a housing having a top wall adapted to hold said holder with said fibrous material suspended therefrom within said housing, means respectively on said top wall and said holder movable relatively into interlocking releasable engagement when said holder is carried by said top wall for holding said holder stationary during beating of said body, a beating element below said top wall supported for generally oscillatory movement back and forth across the space adapted to be occupied by said head when said holder is secured to said top wall, means for so actuating said beater element including a spring adapted to be power loaded and connected with said element, a foot actuated member supported for generally reciprocable movement and operatively connected with said element for moving the latter for so loading said spring when said element is held against said oscillatory movement during said loading, means for releasably holding said element against oscillatory movement for a predetermined time during said loading of said spring and for releasing said element after said predetermined time for moving said element under the power of said spring.

10. A dust mop cleaner for a dust mop head having a main body of fibrous material secured to a holder therefor, said cleaner comprising a support for said mop head adapted to hold said holder with said body suspended therefrom, a beater element supported below said support for generally oscillatory movement in a vertical plane across the space adapted to be occupied by said body when said holder is held by said support, a spring adapted to be power loaded connected with said element, movable means separate from said element and actuatable by an operator for so loading said spring, means for releasing said element after said spring has been so loaded to a predetermined degree for causing said movement of said beater under the power of said spring.

11. A dust mop cleaner for a dust mop head having a main body of fibrous material adapted to be suspended vertically from a holder; a housing having a top wall, sides, and a bottom wall, a beater supported within said housing for generally horizontal oscillatory movement below said top wall, horizontally spaced guide elongated members, below said top wall including corresponding upwardly inclined portions adapted to engage the opposite sides of said body of fibrous material below said holder and adjacent thereto for positioning the body within the path of travel of said beater, means for moving said beater in said generally oscillatory manner.

12. A dust mop cleaner for a dust mop head having a main body of fibrous material adapted to be suspended vertically from a holder; a housing having a top wall, sides, and a bottom wall, a beater supported within said housing for gen-

11

erally horizontal oscillatory movement below said top wall, horizontally spaced elongated guide members below said top wall including corresponding upwardly inclined portions adapted to engage the opposite sides of said body of fibrous material below said holder and adjacent thereto for positioning the body within the path of travel of said beater, means for moving said beater in said generally oscillatory manner, one of said side walls being formed with an opening for said mop head, and a horizontally extending rib supported on said housing for swinging inwardly into said housing between the said guide members and adjacent end of the latter for mov-

12

ing said body into the path of travel of said beaters.

BERT T. INSLEY.
